LOADER

Walter B. Richardson, Bridgton, Maine

Application February 16, 1948, Serial No. 8,540

1 Claim. (Cl. 212—58)

1

This invention relates to improvements in loaders and is directed more particularly to the provision of a new loading apparatus having a special supporting structure which adapts it to be firmly and easily mounted in or on the body of a dump-truck, van, or any other type of vehicle.

It is a particular object of the invention to provide a sturdy, well-braced structure wherein a movable arm member is rigidly supported yet easily manipulated for the loading or unloading operations. As a special feature, there is provided means whereby the arm member may be lifted to desired positions through hydraulic pressure and swung to different positions where it is releasably but firmly held.

As will appear, while the construction is such that the loader is capable of performing very heavy duty, it is simple in form so as to be inexpensive to manufacture and is such that it may be safely and solidly installed on or in relatively lightweight vehicles.

Various other objects and advantages of the invention will become more apparent after a reading of the following description and reference will be had therein to the accompanying drawings, wherein:

In the drawings,

Figure 1 is a side elevational view of the apparatus of the invention with parts broken away for purposes of explanation of details thereof,

Figure 2 is a sectional view on the line 2—2 of Figure 1; and

Figure 3 is a partial side elevation showing a modified arm and link construction.

Referring now to the drawings more in detail, the invention will be fully described.

There is a supporting base 2 which usually will take the form of a heavy plate of metal and this is adapted to be secured in any desired location as by bolts extending through holes 4. What may be called a retaining member, indicated generally by the numeral 6, includes a vertically extending plate 8 welded at 9 to the base 2 and upper and lower horizontally extending retaining plates 10 and 12 respectively, which are welded as at 13 to member 8.

Disposed between these plates 10 and 12 with its rear end normally disposed closely adjacent, but somewhat spaced from plate 6, is an upstanding retaining bracket which includes horizontal upper and lower plates 20 and 22 respectively. Plate 20 underlies plate 10 and plate 22 overlies plate 12 while the opposite sides of said plates 20 and 22 are connected by spaced vertically extending side plates 24.

2

The forward end portions of plates 20 and 22 project outwardly beyond the forward edges of side plates 24, as clearly shown in the drawings, and are for purposes which will presently appear. In any event, each of the horizontal plates 20 and 22 is provided with a pair of spaced openings 26 vertically aligned with a similar pair in the other plate.

In addition the plates 20 and 22 have vertically aligned holes 27 which are aligned with the rear-most openings. Thus a pivot pin 28 may extend downwardly therethrough, as clearly shown in Figure 1, with an enlarged head 29 and stop 30 to prevent displacement but to permit the bracket to swing or swivel between plates 10 and 12 and relative to parts 2 and 8.

In addition, the plates 10 and 12 are each provided with an arcuate row of spaced openings 32 therein, the holes of one row being vertically aligned with those of the other row. The openings 32 are also such that when the bracket is swiveled a selected aligned pair of openings may be brought into coincidence with the forward holes 26 in plates 10 and 12 so that a retaining pin 33 may be dropped through said forward hole 26 in plate 10, through the selected holes 32 in plates 10 and 12, and project downwardly through the forward hole 26 in plate 12.

A head 34 on pin 33 and stop 35 on the lower end thereof serve the same purposes as the similar parts of pin 28. According to the preferred form of the invention there are tubes 36 and 37 which extend between the plates 20 and 22 and are for receiving and guiding the pins 28 and 33 respectively.

On the forward side of the bracket there is a vertically extending tube 40 which is rotatably positioned between the plates 20 and 22 and this is in direct communication with openings 42 provided therein. Extending downwardly and slidably positioned within this tube 40 and holes 42 is a retaining pin 44 having a head 46 and stop 48.

Secured to the forward side of the upper part of this member 40 is a pair of outwardly extending, spaced lugs 50, while extending outwardly from its lower part in substantial parallelism therewith is a pair of lugs 52. Between the lugs 50 there is pivotally held, as by a bolt 54 the inner or lower end of a link member 60.

A hydraulic cylinder 70 has a lower extending portion 72 pivoted as on a pin 74 between ears or lugs 52. The cylinder 70 includes the usual piston 76 with rod 78 movable with the piston 76 in the ordinary manner.

55 A main loading arm or member is indicated at

80. This may take various forms but in any case is formed of rigid metal and of sturdy construction. Preferably it has spaced walls or ears on its lower or inner end for pivotally receiving the outer end of link 60 and pivot pin 82.

The arm 80 is also adapted to receive the outer or upper end portion of part 18 and this may be accomplished by recessing the arm 80, making it channel-shaped or in any other suitable manner. The upper end part 18 is, in any event, pivoted to the loading arm as on pin 84.

It will be appreciated that the outer end of the arm 80 may have associated therewith any one of a varied number of loading devices none of which are shown, such as a crane, shovel, or the like. Obviously the hydraulic cylinder and piston arrangement provides for the accurate and easy lifting and lowering of the loading arm while the special bracket arrangement permits the swiveling motion referred to so that the arm may be swung into various angular positions relatively to its base. That is, the bracket may be pivoted on the pivot pin 28 to a desired angular position relative to the base 2, and then, locked in such selected position by means of inserting the retaining pin 33 through the aligned openings in the ledges 10 and 12 and the plates 20 and 22. Further angular adjustment may be had in this locked position, if desired, since the tube 40 carrying the loading arm 80, is rotatable relative to the pin 44.

The form shown in Figure 3 is substantially similar to that just described. There are spaced walls 124 which are the same as walls 24, and horizontal plates one of which is shown at 120 like plates 20 and 22, previously described.

Heads or knobs 129 and 134 are equivalent to parts 29 and 34 respectively, being disposed on the upper ends of pins adapted to function the same as pins 28 and 33. Here there is a tubular member 140, which is somewhat like tube 40, but it is of greater height than the other tubes so as to project considerably above the plane of the heads 129 and 134.

Secured to this member 140 is a special bracket member 150 which is slotted as at 152 to accommodate plate 120. The upper end portion of bracket 150 extends around the upwardly projecting part of part 140 so as to have a rearwardly extending arm portion 154 while its lower end portion (not shown) is secured to the equivalent of the pair of ears 52 shown in Figure 1.

A retaining pin 144, like pin 44, extends downwardly through the slotted tube 140 and through the forward opening 142 in plate 120. A head 145 is on the upper end of part 144.

At 178 is represented the equivalent of hydraulic cylinder 70 with 178 the same as actuating part 72, the latter being pivoted as by pin 184 to arm 180. A link 160 has its opposite ends pivoted by pins 155 and 182 to parts 154 and 180, respectively. This arrangement has been found to give more lifting power to the whole structure.

I do not mean to confine myself to the exact details of construction herein disclosed but claim all variations falling within the purview of the appended claim.

What I claim is:

A loading device comprising a base, an upstanding member secured at its lower end to said base, a pair of horizontal ledges secured to said upstanding member and extending forwardly therefrom in a superimposed relation, a bracket positioned between said ledges and mounted for pivotal movement in a horizontal plane relative to the latter, said bracket comprising a pair of horizontal superimposed plates, means positioned between said plates and connected to the latter for securing said plates in a fixed relation one to the other, a vertical pivot pin extending through said ledges and said plates adjacent said upstanding member, said ledges being provided with vertically aligned openings adjacent the forward ends thereof, each of said plates being provided with an arcuate row of openings in its intermediate portion, said rows of openings being in vertical alignment with each other and adapted to be brought into selective alignment with the openings in the forward ends of said ledges when said bracket is pivoted, means insertible through the openings in the forward ends of the ledges and selected openings in said plates for securing the bracket in predetermined positions relative to said upstanding member, a vertical tube rotatably mounted between said plates adjacent their forward ends and carried by the latter, an arm pivotally carried by the upper end of said tube, means carried by the lower end of said tube and operatively connected to said arm for moving the latter upwardly and downwardly.
